[57] **CLAIM**

The ornamental design for an artificial nail tip, as shown and described.

DESCRIPTION

FIG. 1 is a rear elevational in accordance with my new design;

FIG. 2 is a front elevational view thereof;

FIG. 3 is a bottom plan view thereof; and,

FIG. 4 is a cross sectional view taken along line 4—4 of FIG. 2.

The characteristic feature of my design resides in the contours of the clip element on the rear surface in combination with the nail tip.
